CLAIM

The ornamental design for a beverage container, as shown and described.

DESCRIPTION

FIG. 1 is a front perspective view of a beverage container showing our new design;

FIG. 2 is a left side elevation thereof, the right side elevation being a mirror image;

FIG. 3 is a bottom plan view thereof; and

FIG. 4 is a rear side perspective view thereof, with handle in open position.

FIG. 1

FIG. 2

FIG. 3

FIG. 4
